Attorney

UNITED STATES PATENT OFFICE

THOMAS J. SEABOCH, OF LENOIR, NORTH CAROLINA

OBSTACLE REMOVING DEVICE FOR COW CATCHERS

Application filed August 5, 1931. Serial No. 555,298.

This invention relates to means for removing obstacles from the rails of a railroad track, the general object of the invention being to provide a pair of depending members attached to the cow catcher of the locomotive and arranged adjacent the rails so that said members will remove obstacles from the rails.

This invention also consists in certain other features of construction and in the combination and arrangement of the several parts to be hereinafter fully described, illustrated in the accompanying drawings and specifically pointed out in the appended claim.

In describing the invention in detail, reference will be had to the accompanying drawings wherein like characters denote like or corresponding parts through the several views, and in which:

Figure 1 is a side view of a portion of a locomotive and a track showing the invention in use.

Figure 2 is a plan view of Figure 1.

Figure 3 is a view of one of the devices.

As shown in these views the device comprises an elongated block 1 having a right angular flange 2 at its upper end said flange having an opening 3 therein and the upper part of the block having a pair of openings 4 therein so that these openings can receive bolts 5 for attaching the device to the cow catcher of the locomotive as shown in Figures 1 and 2.

As shown in these views, two of the devices are attached to the cow catcher, one over each rail so that the devices will act to push objects such as spikes, stones rocks or the like from the rails and thus prevent the train or locomotive being derailed by such articles.

By attaching the devices to the cow catcher in the position shown the devices travel over the rails at an angle so that they act to push the objects to the outer side of the rails and not to cause the objects to slide along the rails.

It is thought from the foregoing description that the advantages and novel features of the invention will be readily apparent.

It is to be understood that changes may be made in the construction and in the combina-

tion and arrangement of the several parts provided that such changes fall within the scope of the appended claim.

I claim:

In combination with a cow catcher of a locomotive, a pair of depending members attached to the cow catcher adjacent the ends thereof, whereby said members will be located above the rails to remove objects from the rails, each member consisting of a block having a flange at its top, said flange and the top part of the block being attached to a part of the cow catcher.

In testimony whereof I affix my signature.

THOMAS J. SEABOCH.
